UNITED STATES PATENT OFFICE.

JOSEF NEUMANN, OF NEW YORK, N. Y., ASSIGNOR TO ISAAC BERNHEIMER
AND JACOB GOLDSMITH, OF SAME PLACE.

IMPROVEMENT IN CAN-SEAMING MACHINES.

Specification forming part of Letters Patent No. **149,599**, dated April 14, 1874; application filed December 11, 1873.

To all whom it may concern:

Be it known that I, JOSEF NEUMANN, of New York city, State of New York, have invented a Compound-Lever Press, to be used in the Manufacture of Oil and other Cans, of which the following is a specification:

The object of the invention is to rapidly fold and press the top and bottom seams of oil and other cans in a peculiar manner, in which it has not been done by machinery heretofore.

The invention is illustrated in detail in the accompanying drawings, in which—

Figure 1 represents a vertical longitudinal section, in line 1 1 of Fig. 2, of the machine, the cam-levers C C C C and some other parts being omitted. Fig. 2 is a plan view of the plate A, with all the jaws in place, shown in such a position as they would be when the treadle B is up. Fig. 3 is a plan view of the plate A, having the bottom plate H' attached, all the jaws being removed. Fig. 4 is a side elevation of the vertical swaging-die g. Fig. 5 is a plan view thereof. Fig. 6 is a vertical diagonal section, in line 2 2 of Fig. 2, of the plate A and all its attachments. Fig. 7 is a plan view of the plate A detached from every other part. Fig. 8 is a plan view of the cam l', which operates the cam-levers C. Fig. 9 is an elevation of the bottom plate H' detached, represented as looking at one corner thereof. Fig. 10 is a vertical diagonal section of all the jaws and the vertical swaging-die g, with a portion of the can-body and the can-bottom inserted, ready to have the seam formed. Fig. 11 is a vertical section of the can-body, such as the machine is calculated to operate on. Fig. 12 is a vertical section of the can-body in line 3 3 of Fig. 11. Figs. 13, 14, and 15 are also sections of the can-body and can-bottom, showing the lower portion of the can-body only, and the various stages of formation of the seam.

The last figures, 10, 11, 12, 13, 14, and 15, are drawn on a larger scale than the preceding figures.

The machine is constructed as follows: A is a square plate, supported at a convenient height by suitable legs. It is provided with a large aperture, a, in its center, and an oblong radiating slot, a', at each of its four cor-

ners. B is a treadle-lever, having its fulcrum at b, attached to a cross-bar, b', of the machine. From this lever all the various motions required in the machine are obtained. C C C C are four cam-levers, which pass through the slots a' a' a' a', some distance below the plate A, and have their fulcrums at d d d d, above the plate A, in certain projections d' d' d' d', cast onto the plate. Each of these cam-levers C transmits a slight horizontal reciprocating motion, in a diagonal direction, to two slides or jaws, e and f, which are guided between the shoulders g⁴ g⁴. The four upper jaws f f f f serve to hold the can in position while the seam is being formed, and their inner edges are therefore shaped to fit the shape of the can-body above and below its shoulder, each embracing a corner of the can-body, and are wide enough to surround the whole square thereof when they have been moved up to the can. The lower jaws e e e e serve to bend the edge of the can inward all around; their inner edges must also conform to the shape of the can. k k k k are four inside jaws, for the purpose of holding the can-body and the can-bottom in shape, and resisting the pressure of the bending-jaws e e while the seam is being formed. These resisting jaws k k are also capable of a slight reciprocating motion in a diagonal direction—that is, they can be contracted and expanded—in which latter position they are shown in all figures. The means by which the expansion and contraction of these resisting jaws k k is effected will hereafter be explained. Their motion is guided in diagonal dovetailed ways h¹, which are provided for them at the upper part of four blocks, h h h h, which are attached to a plate, H, in such a manner as to leave diagonal grooves h² h² between them. At the lower side of the plate H, in the center thereof, there is a vertical sleeve, H', which forms a guide for the vertical stem g¹, which, at its upper end, carries the swaging-die g, which is capable of a slight vertical motion. Its construction is clearly shown in the various figures. Its shape conforms to the shape of the interior of the can-body, and consists of a square frame, having round corners and diagonal arms, which unite in the center, where the stem g¹ is fastened to

the bottom side thereof. The arms of this swaging-die fit in the diagonal grooves h^2 , in which they are at liberty to rise and fall. This swaging-die receives its up-and-down motion from the treadle through a horizontal lever, i , below the plate A , and a connecting-rod, i' . One end of this rod i' is slotted, as seen in Fig. 1, in order to produce the lifting of the swaging-die g only at the last end of the downstroke of the treadle. The stem g^1 of the swaging-die is hollow throughout its whole length, and at its upper end there is a cone, g^2 , inserted, which, operating against the inner ends of the resisting jaws k , causes them to expand when the swaging-die descends—that is, when the treadle is on its upstroke. The contracting motion of the resisting jaws k can be produced by their lower corners coming in contact with certain bevels x made at the interior of the four corners of the swaging-die g , when the said die rises, or by any other suitable means. There is a vertical center-rod, l , which is guided up and down in the bore of the stem g^1 and receives its vertical reciprocating motion from the treadle through a connecting-rod, l' . To this rod is attached a cross, l'' . The lower sides of the four arms, being curved, as shown in Fig. 6, operate as so many cams against the lower ends of the cam-levers C C C C. The inner edges at the upper ends of these cam-levers are furnished each with two projections or teeth, y and z . As the lower ends of the cam-levers move outward on the downstroke of the treadle the teeth y produce the inward motion of the upper jaws f , and the teeth z that of the lower jaws e . The return-motion of the cam-levers may be obtained by a rubber band surrounding the four levers—not shown in the drawings; and the return motion of the upper and lower jaws f and e may be obtained by separate springs attached to each of them—also not shown in the drawings. There is a vertical standard, m , bolted onto the rear part of the plate A , which carries at its upper portion a lever, n , to which is hinged at its front end a square plate, n^1 , somewhat larger than the end of the can. An arm, n^2 , is fastened to the rear part of the lever n , and serves as a counter-weight, its inner edge being at right angles with the lever n . This arm or weight n^2 causes the lever n to be in a position as shown in full lines in Fig. 1 when the treadle is up. A vertical rod, o , being guided in suitable ways at the rear of the standard m , receives a vertical motion from the treadle by means of a connecting-rod, p , which is hinged to the rear part of the treadle behind its fulcrum. When the treadle is carried down the rod o pushes the counter-weight n^2 up to a position, as shown in dotted lines in Fig. 1, thereby moving its lever n and plate n^1 down to a horizontal position, and leaves these parts in that position while the treadle continues its downstroke. The treadle B may be carried down by foot-power, or otherwise, and a counter-weight, (not shown in the draw-

ing,) at the rear portion of the said treadle, may return it to its original position.

The operation of the machine is as follows: When the treadle is up the resisting jaws k k k are expanded and the upper and lower outside jaws have receded. Now, the bottom of the can is placed upon the resisting jaws k k with its flange or edge downward, and the body of the can is placed upon the bottom. Then, the treadle, being forced down, will first cause the bar o to carry down the plate n^1 upon the upper end of the can-body and hold the same firmly down upon the can-bottom and the resisting jaws k throughout the whole operation of forming the seam at the bottom. The treadle, proceeding farther in its downstroke, carries down the cam l' , which moves the cam-levers outward, and the upper jaws f , as well as the lower jaws e , inward. The upper jaws f come up to the can-body and hold it and the flange of the can-bottom firmly between themselves and the edges of the resisting jaws, in which position they are shown in Fig. 10. The lower jaws e advance slightly beyond the upper jaws, and thereby bend the extreme lower edge of the can-body inward, as shown in Fig. 14. The cam-levers moving farther, the lower jaws e can recede from the can by dropping into the notches formed between the two teeth y and z , while the upper jaws f retain their hold on the can. Finally, the treadle, on its last part of the downstroke raises the swaging-die g , which, in the meantime, contracts the resisting jaws to make room for the swaging-die to pass and turn up the edge of the can-body inside of the flange of the can-bottom, when the seam is finished, and of a formation as shown in Fig. 15. Now, the treadle can return to its original position, and the can may be removed from the machine.

I claim as my invention—

1. In a machine or press for forming the bottom and top seams of tin cans, the gravitating arm n^2 , at right angles with the pivoted lever n which carries the plate n^1 , in combination with a vertical sliding bar, o , operated by the treadle, substantially as and for the purpose specified.

2. The outside bending-jaws e , in combination with the outside holding-jaws f and the inner resisting jaws k , operated substantially as and for the purpose specified.

3. The vertical swaging-die g , in combination with the diagonal jaws e and the resisting jaws k , constituting the device for holding the can while the turning of the edge takes place, substantially as described.

4. The inner resisting jaws k k k k , capable of expansion and contraction, constructed and operated substantially as and for the purpose specified.

JOSEF NEUMANN.
